COMMUNICATION SYSTEM

Alfred L. Sprecker, Freeport, N. Y., assignor to
 International Business Machines Corporation,
 New York, N. Y., a corporation of New York

Application January 23, 1935, Serial No. 3,001

10 Claims. (Cl. 178—66)

This invention relates to communication systems and more particularly to printing telegraph systems of the non-synchronous type and applicable to radio transmission.

5 The type of printing telegraph system embodied in the present invention is similar in principle to the system fully described in the application Serial No. 737,013, filed July 26, 1934, by V. M. Bugge,

10 The principle of the system referred to in the said application, instead of depending on the synchronous operation of the transmitting and receiving units, operates on the basis of the transmission of signals of predetermined current values to which the receiving unit will give a definite and different response to each signal.

15 The system comprises in general a keyboard or typewriter similar to that of a conventional typewriter to originate impulses of predetermined current value by depression of the particular character key desired to be transmitted. Each character to be transmitted is represented by one or more impulses of differential current strength and polarity, the particular signal for 20 a selected character sent over the network when the corresponding key is depressed releasing its pulse wheel or disk suitably provided to send the proper code. Each receiving station includes a galvanometer line relay and a line stepping 25 relay, the former responsive to the definite current strength values and polarity of the impulses, whereas the latter is responsive only to the number of the impulses regardless of the impulse current strength and polarity.

30 Due to the particular circuit arrangement embodying the two types of relays just mentioned which are arranged to provide for the conditioning of the proper circuit, the proper character is caused to be recorded at the receiving unit.

35 The present invention applies the system just explained to radio transmission. This procedure may be effected for example, by transforming the various code combinations of impulses representing the signals into separately modulated 40 carrier waves and upon reception interpreting them into code combinations of impulses to separate the receiving printing telegraph unit in a manner similar to the aforementioned method.

45 In the particular disclosure of the present invention one method of effecting the said transmission at the transmitter of combinational pulses to modulated radio frequencies to combination pulses at the receiver, will be described and embodies the use of a plurality of different audio frequencies or combination thereof modulating

the carrier-wave. For illustrative purposes of the above principle, all pulses of positive current may be coded into single audio frequencies; that is, for each increment of positive current values employed, a single audio frequency for each current value is to be employed, while all negative pulses may be coded as two frequencies, and similarly for each increment of negative current values, a different combination of the double frequencies is to be employed, and in the combination of which one common audio frequency may serve as a polarity change for the receiving unit.

5 The in addition thereto the combination code pulses at the transmitting unit may be impressed upon a circuit including therein, a polarized relay, a rectifier and a multistep galvanometer relay. The polarized relay codes the polarity of the pulses received and controls the transmission of the common frequency that may be used in 10 addition to the multi-frequencies representing the individual increments of current values to represent a definite pulse polarity, let us say a negative value. The multi-step galvanometer is sensitive to the rectified current pulses so as 15 to translate the differential current increments into the corresponding single audio-frequencies, in addition thereto the galvanometer is responsive to the number of pulses included in the combination code to impress the corresponding 20 number of pulses on the carrier wave.

25 Upon reception of the modulated carrier, the plurality of radio signals may be impressed upon a circuit including a plurality of tuned circuits, each tuned to a single one of the frequencies employed. Upon the energization of each tuned circuit, a pulse of corresponding current value 30 is initiated. The reception of the said common frequency employed causes the polarity change 35 of the current impulses and upon further description hereinafter it will be understood how these transformed pulses operate the receiving unit in accordance with the transmitting unit and upon the same principle employed in the 40 said prior application.

45 The principal object of the present invention is to provide an improved method and apparatus for the transmission of intelligence.

50 It is another object of this invention to provide a printing telegraph system of radio transmission whereby the selection of the predetermined characters depends solely on the character impulse characteristics.

55 Further and other objects of the present invention will hereinafter become apparent in the ac-

companying specification and claims and shown in the drawings which by way of illustration is what is now considered to be the best mode in which it has been contemplated applying that principle. Other embodiments of the invention employing the same or equivalent principle may be used and structural changes made as desired by those skilled in the art without departing from the present invention and within the spirit 10 of the appended claims.

In the drawings:

Fig. 1 shows one embodiment of the transmitting circuit illustrating the principle of the invention.

15 Fig. 2 shows one embodiment of the receiving circuit.

Fig. 3 shows a form of combinational code system which may be used in conjunction with the system.

20 Referring now to the drawings in which similar parts are designated by the same numerals in the several views, it is believed that a clear understanding of the invention will be had therefrom when considered in conjunction with the 25 following description.

Transmitting unit

Referring now to Fig. 1, a plurality of pulse wheels or disks 14 are shown with a combination 30 of conducting segments 16 thereon. The arrangement and number of conducting segments for each disk corresponds to the code shown in Fig. 3, for example, the character "S" the code of which is current value 1, positive potential and four 35 impulses, namely, three short and one long. Therefore, on the disk 14 for the character "S" four conducting segments 16 are disposed thereon so that the three short pulses of current are conducted before the long segment engages the 40 contacts 17 to transmit the long impulse of its corresponding current value. It is to be noted that for characters represented by a plurality of impulses the last impulse is always a long one the significance of which will be understood as the 45 description progresses. Each disk therefore has disposed thereupon the number of segments to correspond to the number of impulses in its particular code. It is sufficient to mention that upon the depression of a character key of the typewriter (not shown) its corresponding disk 14 is 50 released to complete one revolution, thereby conducting the proper increment of current value, polarity and the number of impulses to the line 19 representing the character. A further description 55 may be had by referring to the said prior application in which the transmitting typewriter and mechanism for releasing the pulse wheels is shown and completely described. Since this mechanism forms no part of the invention, it is 60 deemed unnecessary to repeat such description.

The combinational code of impulses are impressed on circuit 19 comprising a polarized relay 20 adapted to be energized by negative currents so as to position its armature 50 in engagement 65 with contact 51, positive current returns the armature to its normal position as shown in the figure. Also connected to circuit 19 is the bridge rectifier unit 52 which in turn is connected to the coil 53 of the multi-step galvanometer relay 54, 70 so that the positive and negative current values become uni-directional currents energizing the relay coil 53 in degree corresponding to the current values. Four different current values are shown in the code in Fig. 3, and the impression 75 of these current values on the relay coil 53 posi-

tions its armature 55 in engagement with one of the four contacts 56 shown in Fig. 1 to complete a circuit from the radio transmitter and amplifier 57 through conductor 58, armature 55, corresponding contact 56 and frequency generator 59 of any well known type and return conductor 60 modulating the carrier wave accordingly. Galvanometer relay 54 is also sensitive to the number of impulses transmitted by the released code disk so that the particular contact 56 is engaged a number of times corresponding to the number of impulses transmitted so that the radio signal consists of the similar number of pulses. The receiving apparatus is so designed that it is not effected by the contacts 56 for the short 10 interval of time they are engaged by armature 55 while it is positioned in accordance with the current value impressed on the relay coil. Upon energization of relay 20 so that its contact 51 is closed it is seen that the circuit 61 is closed to 20 connect the frequency generator 59 designated f-5 to the transmitter, the purpose of which will be understood as the description progresses.

Therefore, let it be assumed, that the typewriter key corresponding to the letter "S" is depressed. 25 It is understood that its designated pulse wheel 14 is released to send four impulses, three short and one long impulses of current value 1 and positive polarity to the circuit 19. The combination of the different frequencies comprising the 30 signal to be transmitted is shown in Fig. 3, for the letter "S" frequency f-1 is designated. Since the polarity of the impulses impressed on relay 20 are positive, the relay remains inoperative. The relay coil 53 connected to circuit 19 is en- 35 ergized so that its armature 55 engages the contact 1 of the group of contacts 56 to impress the particular frequency f-1 upon the radio transmitter 57. Since four impulses were sent out by 40 the code wheel 14, relay coil 53 is energized four 45 times to impress the frequency f-1 for four timed intervals on the transmitter, the first three intervals of time shorter than the last in accordance with the code for character "S". In this manner the radio signal is transmitted for this 50 character consisting of three short and one long pulses of a definite frequency value.

For the character "O" a long impulse of current value 4 and negative polarity is sent out on circuit 19 by its pulse wheel. This impulse 50 causes the relay 20 to be operated to close the circuit so as to modulate the carrier wave by frequency f-5 and frequency f-4, since the relay coil 53 is energized by current value 4 to 55 position its armature to the contact 4 for one long 55 interval of time; the radio signal for this character consists of one pulse of the combination of frequencies f-4 and f-5.

The method of translating the transmitted signals will now be explained in connection with Fig. 2.

Receiving unit

The various signals are impressed upon the receiver and amplifier 65 in the well known manner to energize the circuit 66 comprising a plurality of filters 67, each one responsive to the individual frequencies f-1 to f-5. Connected to each filter circuit 67 is an individual relay R-1 to R-5 adapted to be operated by its corresponding connected circuit and frequency therefor. Operation of the relays R-1 to R-4 connects the battery 68 to the circuit 69 to impress different current values thereon in accordance with the operation of a particular relay 75

R-1 to R-4. Relay R-1 impresses a current value 1 upon the said circuit, relay R-2, value 2, etc. Similarly, if the relays R-1 to R-4 are operated a number of times, the similar number of impulses of the particular current value are impressed on circuit 69. Operation of relay R-5 by a signal comprising the frequency $f-5$ acts as a regular pole-changer and transfers the negative side of the battery 68 from contact 10 of relay R-5 to its contact 71, the positive side of the battery connected to contacts 72 of the relay R-1 to R-4 and common conductor 73 to contact 74 of relay R-5 is transferred to its contact 75 so that upon operation of relay R-5 the direction of the current flow in circuit 69 is reversed to position the armature 24 of galvanometer relay 21 accordingly. It is to be noted that this relay 21 has eight contact positions and is adapted to position its armature on its contacts 23-1 to 4 in accordance with the current values 1 to 4 impressed on its coil 25.

The direction of movement of the armature is governed by the polarity of the current as indicated in the figure. This galvanometer relay is sensitive to the current values and polarity but not to the number of impulses transmitted and adjusted so that the short impulses are not of sufficient duration to position its armature 24. However, the long impulse which is the last impulse transmitted in the selected code is of sufficient duration to cause the armature 24 to engage its proper contact 23 corresponding to the current value and polarity selected by the relays R-1 to R-4. Therefore, when and only when the long impulse is impressed on this selecting circuit is the relay 21 sufficiently energized to be properly positioned so that the armature 24 can supply current to the conditioned circuits through its particular contact 23, a complete disclosure of which is set forth in the said prior application and therefore, the following brief explanation thereof is deemed sufficient.

Relay 22 connected to the circuit 69 is responsive only to the number of impulses transmitted and closes its contact 26 for each impulse (short and long) to conduct current from positive battery through lines 27 and 28, contact 26, line 30, coil 31, of stepping relay designated 32, normally closed contact 33A and line 34 to negative battery stepping relay 32 is adapted to step its brush or armature 33 ahead to the adjacent contact 36 each time its coil 31 is energized. The additional coil 39 is adapted to return the brush 33 to its normal position as shown in the figure whenever it is energized.

Therefore, for each impulse transmitted, the relay 22 is energized, energizing relay 32 to step its brush arm 33 ahead so as to engage contacts 36 successively and corresponding to the number of impulses transmitted.

Depending on the number of short and long impulses transmitted, the brush arm 33 will be held in constant engagement with its particular contact 36 so that the proper selection of the particular circuit may be made. The final position of the arm 33 during the transmission of a signal is actually the summation of the number of independent impulses received. The brush arm maintains this last position mentioned until the particular letter coil 38 is selected and energized to record the character. The typewriter at the receiving unit is of the type equipped with solenoids 38 and adapted upon the energization of the solenoid to have the key bar depressed to operate the corresponding type bar accordingly.

When the character is recorded relay 40 and coil 39 of relay 32 are energized to release the brush arm 33 and restore it to normal position as indicated in the figure. The energization of relay 40 causes its normally closed contact 33A to be opened and in this manner preventing back circuits to be set up through contacts 36 when the arm 33 is returned to normal position.

It was mentioned hereinbefore that the last impulse for each character is a long impulse, or where the character is represented by a single impulse, this impulse is always of long duration, so that it is seen that the brush arm 33 is always engaging its last corresponding contact 36 when the galvanometer relay 21 is energized to correctly position its armature 24, and for this reason the proper selection of the character letter coil 38 may be made as follows.

The armature 24 of relay 21 will engage one of the contacts 23 when its coil 25 is energized by the impulse of long duration, the particular contact engaged depending on the current strength value and polarity, as has been previously explained. Engagement of contact 23 by armature 24 allows current to be conducted through lines 27 and 28, contact 23, coil of relay 43 to negative side of the line, energizing relay 43 to close its contacts 44 whereupon current is conducted from the source through lines 27 and 45, contact 44, coil of relay 46 to negative side of the line, energizing relay 46 to close its contacts 47. The contacts 47 are arranged so that upon energization, contacts 47a, 47b, 47c, and 47d which are connected to the individual letter coil circuits close immediately to energize its respective coil. Contact 47e is arranged to close a timed interval later; this timed interval is equivalent to the time required to energize letter coils 38, when the contacts 47a to d are closed sufficiently to cause the character to be recorded. In practice, this interval is equal to a fraction of a second so that special relay equipment is not necessary to obtain this time delay.

Contact 47e then closes when the energized letter coils 38 cause the character to be recorded, to conduct current from the source through lines 27 and 48, contact 47e, line 49, lines 50 and 51, coil 39 of relay 32, and coil of relay 40, line 34 to the other side of the line, energizing relays 39 and 40 restoring brush arm 33 to normal position.

A specific example will now be given namely for the character "S", the code of which is 4 impulses, three short and one long impulses of the first increment value and positive polarity.

It was explained how depression of the character key "S" at the transmitting unit caused the release of the pulse wheel 14 for one revolution to impress the impulses on circuit 19, and how the galvanometer relay 53 effected transmission of the radio signal of the four pulses of frequency $f-1$. It was also explained how relay R-1 is energized by the tuned circuit 67 sensitive only to frequency $f-1$ to initiate at the receiver three short and one long impulses of current value 1 and positive polarity, and impress these impulses on circuit 69.

Relay 22 is energized four times to close its contact 26 accordingly, energizing stepping relay 32 four times to position its brush arm 33 on its contact 4. The first three impulses are of short duration and therefore are not sufficient to energize galvanometer relay 21 to position contact arm 24 on its proper contact. However, the impulse of longer duration causes the arm 24 to engage contact 4 of relay 21 of the positive group of

contacts, since the current strength is of the first increment value and positive polarity. Relay 43 is now energized, closing its contact 44 to energize selector group relay 46 and close its contacts 47a, 47b, 47c, and 47d.

Brush arm 33 of relay 32 has been positioned to its contact 4, so that when contacts 47 close, a circuit is established through letter coil 38 representing "S" to be energized to cause a record to be made of the said character. Immediately upon recording the character "S", contact 47e is closed to energize coil 39 of relay 32 and relay 40 causing the contact arm 33 to be reset to normal position and condition the circuits so as to enable other character selections corresponding to the characters transmitted.

Similarly, for the character "O" the code of which is a long impulse of current value 4, negative polarity and a combination of frequencies $f-4$ and $f-5$.

It was described how the frequencies are transmitted to impress the signal on circuit 66 (Fig. 2). Relays R-4 and R-5 are energized to initiate an impulse of current value 4 and negative polarity. It was explained how relay R-5 reversed the battery connections upon energization to reverse the direction of the current flow in circuit 69.

The polarized relay 20 at the transmitter may be adjusted so as not to be sensitive to the number of impulses impressed on circuit 19, so that when four impulses, let us say, are impressed on the said circuit, relay 20 is slow to release and not responsive to the short timed interval of deenergization between transmission of the impulses so that the frequency $f-5$ during the entire timed interval required to transmit the signal, would be impressed on the carrier wave and maintain relay R-5 at the receiver energized for this period when signals representing negative polarity are transmitted, and in this manner insure that only negative pulses are impressed on circuit 69.

When the said impulse representing character "O" is impressed on circuit 69, relay 21 is energized to position the arm 24 on contact 4 of the negative group of contacts, energizing the corresponding relay 43 and relay 46 to close its contacts 47a to d. Also stepping relay 32 was energized to step its arm 33 to contact 1, thereby establishing a circuit through the letter coil 38 representing "O" to record this character in a manner explained hereinbefore.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a communication system, means to initiate character signals consisting of impulses having different current values and polarity, a plurality of sources of different frequencies, means to select certain frequencies from the said plurality in accordance with the current values of the initiated signals to modulate a carrier wave accordingly, means adapted to control the selection of one of said frequencies in addition to other selected frequencies to represent a definite polarity, means to transmit and receive the modulated carrier wave, means associated with the receiving means to transform the carrier wave modulated

by the selected frequencies into character signals including means responsive to the additional selected frequency to determine the polarity of the transformed character signals so as to correspond to the initiated character signals.

2. In a communication system, means for initiating signals consisting of code combinations of impulses having predetermined characteristics comprising different current values and polarity, means for modulating a carrier wave in accordance with the said initiated impulses, means to transmit and receive the modulated wave, a plurality of circuits corresponding to the said signals, means associated with the receiving means to transform the modulated wave into signals consisting of code combinations of impulses having predetermined characteristics to correspond to the initiated impulses, and means responsive to the impulse characteristics and to the number of impulses included in the code to select from the plurality of circuits those which correspond to the initiated signals.

3. In a printing telegraph system, means for initiating character signals consisting of code combinations of impulses having different current values and polarity, a source of a plurality of different frequencies, means to translate said signal code combinations into code combinations of said frequencies, receiving means adapted to re-translate said code combinations of frequencies into said original code of impulses having different current values and polarity, and a work circuit selectively controlled by the last mentioned impulses of the original code.

4. The invention set forth in claim 3 in which means are provided to control the selection of an additional frequency representing a definite polarity of the impulses and thereby controlling the said receiving means in re-translating the code combinations of frequencies so that the polarity of the said last mentioned impulses corresponds to the said initiated impulses.

5. In a communication system, means for initiating signals consisting of code combinations of impulses having predetermined characteristics comprising different current values and polarity, a source of a plurality of different frequencies, means to translate said signal code combinations into code combinations of said frequencies, receiving means adapted to re-translate said code combinations of frequencies into said original code of impulses having predetermined characteristics, and means responsive to and controlled selectively by and in accordance with the impulse characteristics and the number of impulses included in said code.

6. The invention set forth in claim 3 in which the said translating means includes a selective, multi-position relay device to control the selection of the said frequencies.

7. The invention set forth in claim 3 in which the said receiving means includes a plurality of electrically tuned circuits for the different frequencies whereby each tuned circuit energized controls the operation of an individual relay device.

8. The method of transmitting and receiving printing telegraph signals which comprises initiating character signals having different current values and polarity and number of impulses, translating said initiated character signals into various frequencies or combinations thereof, transmitting the said frequencies or combinations thereof to a receiving station, translating the said frequencies into the original character signals

having said different current values and polarity, and operating a recorder in accordance with the last mentioned translated character signals.

9. The method of transmitting and receiving 5 character signals which comprises initiating signals consisting of code combinations of impulses having predetermined characteristics comprising different current values and polarity, translating said initiated code combinations of impulses into 10 code combinations of various frequencies, transmitting said frequencies to a receiving station, translating the said frequencies into the original code combinations of impulses having the said predetermined characteristics and selecting particular 15 circuits from a plurality of circuits in accordance with the last mentioned impulse characteristics and number of impulses in said code.

10. The method of transmitting and receiving character signals which comprises initiating signals consisting of code combinations of impulses having predetermined characteristics comprising different current values and polarity, translating 5 said initiated code combinations of impulses into various frequencies or combinations thereof, transmitting the said frequencies to a receiving station, translating the said frequencies into the original code combinations of impulses having 10 the said predetermined characteristics, selecting particular circuits from a plurality of circuits in accordance with the last mentioned code combinations of impulses and energizing the selected circuits upon receipt of a predetermined impulse. 15

ALFRED L. SPRECKER.
